UNITED STATES PATENT OFFICE.

PERRY E. REYNOLDS, OF KING CITY, MISSOURI, ASSIGNOR OF TWO-THIRDS
TO GEORGE W. LAWSON AND JACOB E. KESSLER, OF SAME PLACE.

CARPET AND WEATHER STRIP COMBINED.

SPECIFICATION forming part of Letters Patent No. 350,396, dated October 5, 1886.

Application filed April 27, 1886. Serial No. 200,339. (No model.)

To all whom it may concern:

Be it known that I, PERRY E. REYNOLDS, a citizen of the United States, residing at King City, in the county of Gentry and State of Missouri, have invented certain new and useful Improvements in a Combined Carpet-Strip and Weather-Strip; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15. Figure 1 of the drawings is a representation of this invention, and is a top view, the door-frame being in section. Fig. 2 is a vertical section.

My invention relates to carpet-strips and 20 weather-strips combined; and it consists in the construction and novel combination of parts, as hereinafter described, and pointed out in the claims.

Referring by letter to the accompanying 25 drawings, A designates the sheet-metal bottom plate of the weather-strip, which is provided with an upwardly-projecting integral flange, B, along its inner or rear edge, which extends from end to end of the bottom plate.

30 C is the door-frame, and D the door-sill upon which the bottom plate, A, rests.

E designates the cast-iron top plate, which is provided along its inner edge with a downwardly-projecting integral inclined flange, F. 35 In its upper face the top plate, E, is provided with a longitudinal groove or gutter, G, having slots H I J in its bottom, to permit the water to pass through onto the bottom plate, A, by which it is carried to the outside of the 40 door upon the door-sill. The bottom plate, A, is provided with four ribs, K K' K² K³, on its upper face, one rib being located at each end, and the two others being located intermediate of the end ribs. These ribs rest on 45 the bottom plate and support the upper cast-plate above it, so as to form a water-space between said plates.

L and L' are shouldered end pieces of wood, 50 which rest upon the door-sill at the ends of the latter and fit the contour of the inner faces of the door-frame immediately above the door-sill D and directly beneath the lower edge, M, of the door N. The casting or upper plate,

E, is secured in place by screws P, driven down through the ribs of the bottom plate 55 and through the bottom plate into the door-sill itself. The wooden end pieces, L L', may be cut and reduced to permit the weather-strip to be fitted to doors of different widths.

Q designates an iron slat, which is used 60 upon the weather-strip in winter time along the outer face of the door, to prevent snow and wind from entering beneath the door when closed. The wooden end pieces enable the weather-strip to be fitted to any door without 65 marring the door-jambs. The incline bottom plate is secured to the under faces of the ribs K K' K² K³ by screws or otherwise, and the rear or inner edge of said bottom plate is turned up to flange B, which prevents the 70 water from running off at said flanged edge. The end blocks are notched in order that they may fit the door-frame, and are made of wood in order that they may be cut down if necessary, to fit the door-frame, should said 75 blocks when purchased be of improper size. This could not be done were said end blocks made of metal. The bottom plate is secured to the end ribs and intermediate ribs to give it the required incline that will cause the 80 water to run off quickly.

Having described my invention, what I claim, and desire to secure by Letters Patent, is—

1. The combination, with the door-frame and door, of the shouldered end pieces, the transversely-grooved inclined intermediate ribs, the bottom plate provided with the upturned flange along its inner edge and secured to the lower faces of the inclined ribs, and the 90 top plate provided with the front incline, and the rear incline and the longitudinal gutter located between said inclines and provided with slots in its bottom, substantially as specified.

2. The combination, with the door-frame, door, shouldered end pieces, inclined ribs, and the bottom plate and top plate, of the iron slat secured to the end pieces in front of the lower edge of the door, substantially as specified.

In testimony whereof I affix my signature in presence of two witnesses.

PERRY E. REYNOLDS.
